UNITED STATES PATENT OFFICE.

HAZEN H. PERKINS, OF KEWANEE, ILLINOIS.

HUSKING-PIN.

SPECIFICATION forming part of Letters Patent No. 380,516, dated April 3, 1888.

Application filed February 8, 1887. Serial No. 226,925. (No model.)

To all whom it may concern:

Be it known that I, HAZEN H. PERKINS, a citizen of the United States, residing at Kewanee, in the county of Henry and State of Illinois, have invented certain new and useful Improvements in Husking-Pins, of which the following is a specification.

This invention relates to corn-husking pins; and it consists in features of construction and combinations hereinafter described and claimed.

In the accompanying drawings, which illustrate my invention, Figure 1 is a perspective showing the completed device; Fig. 2, a sectional elevation of the husking-pin, lengthwise of the pin, and an elevation of the strap; Fig. 3, an enlarged sectional elevation of the larger end of the pin; Fig. 4, a transverse sectional elevation of the husking pin and strap in line *x*

x in Fig. 2.

Referring to the drawings by letter, the same letter indicating the same part in the different figures, A represents the pin, formed, preferably, of steel, but it may be of any other suitable or preferred material, and has through it two transverse holes, *a* *a'*. One end, *A'*, of the pin A is pointed in an ordinary manner, and the other end, *A''*, is contracted or reduced in size, and is screw-threaded, as shown. A binding-sleeve, B, fits over the larger end of the pin, and has a hole, *b*, corresponding to or approximately coincident with the hole *a'* in the husking-pin. A screw-threaded nut or sleeve, C, is fitted on the contracted end *A''* of the pin, and is provided with a beveled forward end, which fits into or against a similarly but oppositely shaped end of the sleeve B. The pin A also has fixed thereto a loop, D, nearer the hole *a'* than the hole *a*, as shown.

E is the strap, one end of which is passed through the hole *a* and doubled back upon itself to secure it in said hole in an ordinary manner. The strap is then passed through the loop D, and then through the holes *b* and *a'*,

respectively, in the sleeve B and pin A, as shown. By turning the nut C the binding-sleeve B will be forced forward to bring the holes *b* and *a'* out of line, and thereby clamp and firmly hold the end *e* of the strap E.

The strap E moves freely and easily through the loop D, and hence can adjust itself properly on the fingers of the hand of the operator, as indicated by dotted lines at Fig. 2, and when so adjusted its end *e* can be taken hold of to draw it into proper position, and then it may be fixed by turning the nut C, as hereinbefore described. This freedom of movement of the strap in the loop D will also cause the strap to fit and adjust itself to the fingers of the operator in varying conditions, as will occur in the operation of husking, and thus greatly reduce the fatigue of the fingers of the person using this pin in husking.

Having thus described my invention, what I claim as new, and desire to secure by Letters Patent, is—

1. In a husking-pin, in combination, a pin, A, having holes *a* *a'*, loop D, and contracted screw-threaded end portion, *A''*, with a binding-sleeve, B, having the holes *b*, corresponding with the hole *a'* in pin *A''*, nut C, and strap E, one end of which is secured in the hole *a*, and which passes loosely through the loop D and through the coincident holes in the binding-sleeve and the husking-pin, substantially as and for the purpose specified.

2. In a husking-pin, in combination, a pin having holes *a* *a'*, loop D, and screw-threaded end *A''*, strap E, binding-sleeve B, having the holes *b*, corresponding with the hole *a'* in pin *A''*, and nut C, substantially as and for the purpose specified.

In testimony whereof I affix my signature in presence of two witnesses.

HAZEN H. PERKINS.
